TYPING CORRECTION SHEET

Nicholas Seccafico, Jr., Seldon, N.Y. (% Carbon Paper
Corporation, 235 Robbin Lane, Syosset, N.Y. 11791)

Filed May 11, 1973, Ser. No. 359,275

Term of patent 14 years

Int. Cl. D19—03

U.S. Cl. D59—2 A

FIG. 2

FIG. 1

FIG. 4

FIG. 3

FIG. 1 is a top plan view of a typing correction sheet showing my new design;

FIG. 2 is a bottom plan view of the sheet;

FIG. 3 is a top plan view of another embodiment of the typing correction sheet; and

FIG. 4 is a bottom plan view thereof.

The sheet is of nominal thickness.

I claim:

The ornamental design for a typing correction sheet, as shown and described.
